US0D1107237S

(12) **United States Design Patent** (10) **Patent No.:** **US D1,107,237 S**
(45) **Date of Patent:** **** Dec. 23, 2025**

(54) **MILLING MACHINE FOR DENTAL MATERIALS**

(71) Applicant: **DGSHAPE Corporation**, Shizuoka (JP)

(72) Inventors: **Youichiro Ogawa**, Hamamatsu (JP); **Koji Owada**, Hamamatsu (JP); **Masaki Nakabayashi**, Hamamatsu (JP); **Osamu Takenaka**, Hamamatsu (JP)

(73) Assignee: **DGSHAPE Corporation**, Shizuoka (JP)

(**) Term: **15 Years**

(21) Appl. No.: **35/517,557**

(22) Filed: **Jun. 23, 2022**

(80) **Hague Agreement Data**

Int. Filing Date: **Jun. 23, 2022**

Int. Reg. No.: **DM/221727**

Int. Reg. Date: **Jun. 23, 2022**

Int. Reg. Pub. Date: **Jun. 23, 2023**

(57) **CLAIM**

The ornamental design for milling machine for dental materials as shown and described.

DESCRIPTION

1. Milling machine for dental materials

1.1 : Perspective

1.2 : Front

1.3 : Back

1.4 : Left

1.5 : Right

1.6 : Top

1.7 : Bottom

The oblique line shading shown in the reproductions is used to denote claimed surfaces of the milling machine for dental materials that are transparent; the details of the surfaces as
